UNITED STATES PATENT OFFICE.

SIMON YASULAITIS, OF HOBOKEN, NEW JERSEY.

SELF-BALANCING AIRSHIP.

Application filed November 18, 1922. Serial No. 601,798.

To all whom it may concern:

Be it known that I, SIMON YASULAITIS, a citizen of the United States, residing at Hoboken, county of Hudson, and State of New Jersey, have invented certain new and useful Improvements in Self-Balancing Airships, of which the following is a specification.

This invention relates to improvements in air craft particularly aeroplanes having more specific reference to an aeroplane adapted automatically to resume its normal flying position and to balance itself if gone into a nose dive or tail spin from which the usual engine, plane or rudder manoeuvres of the operator fail to extricate it.

It is the principal object of the invention to provide such a flying machine with a movable auxiliary plane in front of the customary fixed planes which is automatically operated to sustain the plane and to return it into its normal, substantially horizontal position while the nose or tail of the plane is tilted so as to assume a dangerous angle approximately vertical to the plane of its usual direction of flight.

Another object of the invention is the provision of means for automatically operating the movable auxiliary front plane to set it at an appropriate angle as soon as the tilting angle of the aeroplane towards the front or rear exceeds a certain degree.

A further object of the invention is the provision of means for normally holding the auxiliary front plane on the same level with the fixed planes so as not to interfere with the normal flight of the machine, and of means for automatically setting the auxiliary plane at a certain angle to the plane of said fixed planes if the angle of deviation of the aeroplane from the horizontal plane at the front or rear exceeds a certain degree.

A still further object of the invention is the provision of a plane equipped with means for automatically locking the auxiliary plane in its inclined or operative position.

These and other objects of my invention will become more fully known as the description thereof proceeds and will then be specifically pointed out in the appended claims.

In the accompanying drawings, forming a material part of this disclosure:

Figure 1 illustrates an aeroplane constructed according to the present invention in a nose dive.

Figure 2 is a side view of the same.

Figure 3 is a view similar to Figure 2 with the front part of the body broken away to disclose the arrangement of the parts in its interior.

Figure 4 is an end view looking in the direction of line 4—4 of Figure 3.

Figure 5 is a top plan view of the aeroplane with one of the planes partly broken away.

Figure 6 is a fragmentary top plan view of a modified form of plane actuating mechanism, and

Figure 7 is a side view thereof.

As illustrated, my improved aeroplane comprises the customary elongated hollow body or housing 10, consisting of floor 11, vertical converging side walls, flat roof 12, tail piece or rudder 13, pit or car 14 and nose 15.

As one example of the possibilities to practically execute my invention, a bi-plane is illustrated in the drawings, it is however, to be understood that the same is applicable to any type of flying machine.

The two superposed planes 16 and 17 are connected in the ordinary well known manner by a plurality of posts 18, and the lower plane 16 is secured to the body 10 in any well known suitable manner.

The body or housing 10 of the machine is supported, when the machine is on the ground, by means of the front pair of wheels 19 and rear wheel 20 respectively, mounted on axles 21 and 22 carried in brackets 23 and 24, secured to the underside of the floor 11. The aeroplane is driven by an engine 25 of any suitable type operating any desired number of propellers conveniently located, one of which, 26 is shown.

The device is however also capable of being used with gliders or aeroplanes not propelled by engines.

A frame consisting of a plurality of substantially horizontal upper front bars 27 and inclined lower bars 28 is arranged in front of the body at a certain distance therefrom

which may be varied with the various types of machines in order to obtain the best possible results.

The inner ends of upper bars 27 are secured to the upper plane 17, and the inner ends of the lower bars 28 are secured to the lower plane 16 in any suitable well known manner. The outer ends of upper and lower bars are connected at their meeting points 10 by means of suitable brackets 29 or otherwise.

Intermediate their lengths, the upper bars are connected by means of cross-rods 30, while the lower bars are similarly connected 15 by means of cross-rods 31, and near their front ends and meeting points with the upper rods 27, the lower rods are connected by a transverse bar or rod 32.

The front edge of an auxiliary plane 33 20 is movably secured by means of a plurality of loops or links 34 to the bar 32, and cables 35 and 36 are secured intermediate their ends to the rear edge of plane 33 as indicated at 37 and 38 respectively.

These cables are guided over rollers 39 on lower cross bars 31 and rollers 40 on upper cross bars 30. The ends of cables 35 and 36 are secured to the ends of levers 37 and 38 respectively secured to the outer ends of a transversal shaft 39 rotatably mounted flush with the upper edge of body 10 in suitable bearings 40 and 41 secured to two of posts 18. This shaft 39 carries secured thereto, with its lower end for lateral movement a lever 42, adapted to engage approximately at its upper end between the teeth of a toothed segment 43 secured with its upper end to the underside of upper plane 17 and with its lower end to the bottom 11 of the body 10, and laterally disposed to one of the inner walls of the body.

A shaft 44 is transversely arranged in pit 14 and carries rotatably in approximately its center a laterally displaceable double hook 45, from the lower hooked end of which a weight 46 is suspended, while its upper hook-shaped end is adapted to be laterally engaged by the hook-shaped upper end of a strong spring 47, the lower end of which is coiled around a transverse stub shaft 48 within the pit near its front end.

An angle piece 49 is secured to the bottom 11 behind weight 46 and is arranged to normally limit the rearward swinging motion of the suspended weight 46, but its upright arm 50 is made of elastic material or elastically secured to its foot part so as to have a rebounding effect on the weight in order to bring it to action during a tail spin, 60 as will be hereafter more fully described.

In the modified form of my invention, the spring 51 is wound around a cross shaft 52 resting with its ends in the side walls of the body 10. One end of the spring 51 is 65 secured in one of these side walls as at 53,

while its other end is bent, as at 54 to grip under lever 55 secured to shaft 52 for lateral displacement, and normally engaging the teeth of a segmental element 56.

The bent end 54 is adapted to be engaged 70 by the upper end of double hook 57 displaceably and rotatably secured intermediate its hook-shaped ends to a transversal shaft 58; the lower end of this double hook carries a weight 59, and a yielding 75 angular stop 60 is secured to the bottom of the pit or car.

The device operates as follows:

During the normal flight of the aeroplane, the auxiliary plane 33 is held by means of 80 the taut cables 35, 36 attached to its rear edge, against the underside of the upper frame bars 27, or in a horizontal plane with the fixed planes, while the lever 42 is engaged between the teeth of the segment 43 85 as best shown in Figure 3. In this position the upper hook end of double hook 45 engages the upper end of spring 47 which grips underneath lever 42 as illustrated in Figure 3.

If now the aeroplane should make a nose dive exceeding a certain angle, the weight 46, suspended from hook 45, will swing forward, rotate hook 45 around shaft 44 and disengage it from spring 47, which operation will release lever 42 from its engagement with the teeth of the segment 43 to turn shaft 39, to which the lower end of lever 42 is secured, under the action of cables 35 and 36 which will be slackened and the weight of plane 33 which will cause a lowering of its rear edge so that the auxiliary plane will assume a position at an inclination to the plane of the fixed planes acting in the same manner as an altitude rudder 105 and lift the front of the plane back to its horizontal plane while lever 42 under the action of rebounding spring 47 is pushed back into engagement with the segment 43 thus locking the auxiliary plane in its inclined position.

As soon as the plane assumes again its position for flying, the auxiliary plane 33 is lifted again by means of the cables and lever 42, to assume again a horizontal position, level with the plane of the fixed planes and the parts are secured in this position by engaging hook 45 again with the end of spring 47 which is then again resting on top of lever 42 in engagement with the teeth of toothed segment 43.

A falling of the aeroplane in a tail spin will be successfully prevented by the rebounding means 50 in rear of weight 46 which will act to throw weight 46 upward 125 far enough to release lever 42 holding the auxiliary plane elevated as described above, and the same will also assume an inclined position tending to right the plane again.

The modified form of my invention il- 130

lustrated in Figures 6 and 7 shows the spring 51 wound around a transversal shaft and secured with one end to the car body, while its other end is kept down by its engagement with the weight hook 57.

It will be clear that upon release of spring 51 by hook 57 when the weight swings forward, the bent end 54 of spring 51 will release lever 55 from its engagement with the 10 teeth of segment 56 and will turn shaft 52 which will allow the weight of the plane 33 and cables 36 to move the plane into an inclined position to the plane of the fixed planes as described above with respect to the 15 preferred form of my device.

The principles involved will be clear to any one well versed in aviatics, and practical experiments with models have shown the correctness of my theory as a plane held in 20 a nose dive or tail spin from which it cannot be extricated by the usual engine, plane or rudder manoeuvres, will be automatically brought back into its normal horizontal position upon the release of the auxiliary 25 plane by the weight and said auxiliary plane will assume an angle to the fixed planes which will be sufficient to righten the plane.

It will be clear that even if lever 42 should be thrown out of engagement with the 30 segment when locking the auxiliary plane in its inclined operative position, the upper frame bars will hold the plane against upward tilting.

Changes may evidently be made in the 35 general arrangement as well as the construction of the minor details of my invention without departing from the scope and spirit of my invention or the principles involved.

Having thus described my invention, what I claim as new and desire to secure by Letters Patent is—

1. An air craft comprising an auxiliary plane, means for securing said plane in front of said craft, cables for normally holding said auxiliary plane in one plane with the plane of the fixed planes, means for normally holding said cables taut, means for automatically releasing said holding means to allow a dropping of said auxiliary plane into inclined position to the plane of the fixed planes for stabilizing the falling craft, and means for locking the parts after the operation of said releasing means.

2. An air craft including supporting planes, an auxiliary plane in front of and secured to said supporting planes, means for normally holding said auxiliary plane in its horizontal inoperative position to act as supporting plane, means brought to action by the fall of the craft towards the front and rear for automatically releasing said auxiliary plane by said holding means to drop by its own weight into its inclined operating

65 position to righten the falling craft, and

means for locking said plane in its inclined position.

3. An air craft comprising a body, a pair of stationary planes secured to said body, a frame attached to said planes, an auxiliary 70 movable plane in said frame, means for normally holding said auxiliary frame in horizontal position, a weight suspended in said body adapted to tilt forward and backward when said craft goes into a nose dive and tail 75 spin to release said holding means for allowing said auxiliary plane to assume an inclined position to said fixed planes, and means for automatically locking said auxiliary plane in its inclined position. 80

4. An air craft including fixed superposed planes, a frame in front of said planes, an auxiliary plane movably secured in said frame, a shaft, links secured at the ends of said shaft, cables secured intermediate their 85 ends to said auxiliary plane and having their ends secured to said links, means connected with said shaft for normally holding said cables taut to hold said auxiliary plane in inoperative position, means for locking said 90 cable holding means; means for automatically releasing said locking means when said craft is going into a nose dive and tail spin, to release said cable holding means, and means for locking the parts in their positions 95 after the operation of said cable holding means.

5. An air craft including two fixed superposed planes, posts for connecting both planes, a frame in front of said planes including a set of bars connected at one of their ends to the upper plane and a set of bars connected at one of their ends to said lower plane, brackets for connecting the meeting opposite ends of said two sets of bars, an auxiliary plane connected movably at its front edge to said frame near the meeting ends of said two sets of bars, a pair of brackets secured to two of said posts, a shaft journaled in said brackets, links secured at 110 the ends of said shafts intermediate their ends, cables secured intermediate their ends to the rear edge of said auxiliary plane and with their ends to the ends of said links, means for normally holding said cables taut 115 to hold said auxiliary plane in a horizontal inoperative position, means for automatically releasing said cable holding means to slacken said cables for allowing a dropping of said auxiliary plane into a position inclined to the plane of said fixed planes, upon the craft going into a nose dive and tail spin, and means for locking said auxiliary plane in its inclined operative position. 120

6. In an air craft, a movable auxiliary 125 plane in front of said craft, a frame comprising two sets of bars adapted to be secured with one of their ends to said craft and meeting at their opposite ends, brackets for connecting the meeting ends of said two 130

sets of bars, cross-bars for connecting the bars of each set, links connected to one of said cross-bars for movably connecting the front edge of said auxiliary plane to said frame between the two sets of bars, cables secured intermediate their ends to the rear edge of said auxiliary plane, rollers on two of said cross-bars for guiding said cables, a shaft, links at the ends of said shaft to the outer ends of which said cables are secured, a lever secured to said shaft adapted to rotate the same, means for connecting said lever to said shaft and allowing a lateral movement of said lever, means for normally locking said lever to hold said cables taut, means for locking the parts in their cable taut holding position, means for automatically releasing said locking means to slacken said cables for allowing a dropping of said auxiliary plane into inclined position to righten the falling craft, and means for locking the parts in their positions after the operation of said releasing means.

7. In an air craft comprising an auxiliary front plane, means for normally holding said auxiliary plane in its horizontal inoperative position, a shaft to which said means are connected, a lever on said shaft, a spring engaging said lever, means for allowing a lateral displacement of said lever, a double hook, its upper end adapted to engage said spring, a weight suspended from the lower end of said double hook, a shaft to which said double hook is rotatably secured, and means adapted to be engaged by said lever and to lock the same when said double hook is in engagement with said spring and when said spring has been released by the motion of said weight towards the front by the fall of the craft to release said first named holding means.

8. In an air craft of the class described, a movable auxiliary plane in front of said craft spaced therefrom, means for holding said plane in its normal horizontal inoperative position, and a transversal shaft in the body of said craft, a double hook rotatably and slidably mounted on said shaft, a weight suspended from the lower hook of said double hook, the upper hook of the same engaging said first named means and adapted to be disengaged therefrom when said weight is swinging forward upon the going of said craft into a nose dive for allowing said auxiliary plane to assume an inclined operating position to righten the craft, and means for locking said auxiliary plane in its inclined position.

9. In an air craft of the class described a frame secured at the front of said craft spaced therefrom, an auxiliary plane, links secured to the outer front edge of said plane and to the front cross-bars of said frame for allowing a swinging of said plane around said front cross-bar, the longitudinal

bars of said frame adapted to limit the swinging motion of said plane, rollers on said frame, a pair of cables secured intermediate their ends to the rear edge of said plane, guide rollers on said frame over which said cables are guided, a rotatable shaft, stationary links secured to the ends of said shaft intermediate their ends provided with eyes at their ends to which the ends of said cables are secured, a lever secured with its lower end to said shaft for lateral movement and adapted to rotate said shaft, means adapted to be engaged by said lever to lock the same in a plurality of positions, a spring adapted to grip with its upper free end over said lever, a double hook, a transversal shaft to which said double hook is rotatably secured, a weight suspended from the lower end of said hook, the upper end of said hook adapted to engage said spring to hold said spring and lever in the position for tautening said cables and lock the auxiliary plane in its horizontal inoperative position, said weight adapted to swing forward under the motion of the craft going into a nose dive to release said hook from said spring for slackening the cable to allow a dropping of said auxiliary plane into its operative position, to righten the craft, said lever adapted to be released from its holding means upon the disengagement of said hook and spring and to be reengaged after the slackening of the cables and dropping of the auxiliary plane into its operative position, and means for limiting the backward movement of said suspended weight.

10. In an aeroplane having a body and stationary planes, a movable auxiliary plane in front of said stationary planes, means for normally holding said movable plane in one level with the plane of the upper of said stationary planes, a pair of cables, links to the free ends of which the ends of said cables are secured, a shaft for said links intermediate their ends, a lever secured to said shaft for lateral displacement, a toothed segment secured to said body adapted to be engaged by said lever, a spring secured with its lower end to the bottom of said body and engaging with its upper bent end the lower part of said lever, a transversal shaft in said body and a double hook rotatably and slidably held intermediate its ends on said transversal shaft, a weight suspended from the lower end of said double hook for normally holding the bent free end of said spring in engagement with the upper end of said double hook and the lever in engagement with the teeth of said segment for holding said cables taut, but allowing a release of the parts upon the swinging forward of the weight under the motion of the craft in a nose dive, to slacken said cables, to lower said auxiliary plane into inclined

- position and a returning of said lever into engagement with said segment for locking said auxiliary plane in its inclined position and rebounding means for causing the weight 5 to perform the functions of releasing said lever and reengaging the same with said segment when said craft goes into a tail spin.
11. In an aeroplane, a body having a pit, a transversal shaft in said pit, a double hook 10 loosely mounted intermediate its ends on said transversal shaft, a weight secured to the lower end of said double hook, an auxiliary plane, cables for holding said plane normally in a substantial horizontal 15 position, means for tautening said cables allowing a locking of the same in taut position by the engagement of the upper end of said double hook with said tautening means, for allowing a release of said tautening means upon the tilting of the craft into 20 a nose dive to allow said auxiliary plane to assume an inclined position tending to righten the aeroplane, means for locking the auxiliary plane in this position, and re- 25 bounding means for allowing said weight to execute the identical functions upon the aeroplane executing a tail spin.
12. In an airship, an auxiliary plane, means for holding said auxiliary plane normally in a substantial horizontal position, 30 means for automatically guiding said auxiliary plane into an inclined nose supporting position when the ship goes into a nose dive, means for locking said auxiliary plane 35 in said latter position, and means for allowing an operation of said guiding means when said ship goes into a tail spin.
13. In an airship a pendulum weight, means automatically operated by said pendulum weight to stabilize the nose of said airship in a nose dive and returning the ship into its normal flying position, means also operated by said weight to lock said stabilizing means during the stabilizing operation, and means for rebounding said weight to perform identical functions when said ship goes into a tail spin.
14. In an airship a pendulum weight, means for stabilizing said ship to guide it
- out of a nose dive automatically operated 50 by said weight, and means for limiting the rearward swinging of said weight, said last named means adapted to rebound said weight for operating said stabilizing means to guide said ship out of a tail spin. 55
15. In an airship, a triangular frame, fixed planes and posts connecting the same forming the base of said frame, cross-bars in said frame, a movable auxiliary plane in said frame movably secured at its front 60 edge to the front cross-bar in said frame, means for holding said plane normally in substantial horizontal position within said frame, means for locking the parts in this position, and means for automatically releasing said locking means to guide said auxiliary plane into an inclined position for stabilizing the ship when executing a nose dive, a spring controlled locking lever 65 allowing the release of said parts and adapted to lock the same again after said release for locking said auxiliary plane in its inclined position during the stabilizing operation. 70
16. In an aeroplane, a plurality of stationary planes, posts connecting each pair of said planes, a triangular frame secured to a pair of said planes in front of the same, brackets forming the apex of said frame, a cross-bar near said brackets, an auxiliary plane within said frame, links 80 for movably connecting the outer edge of said auxiliary plane to said cross-bar, means for normally holding said auxiliary plane in horizontal position within said frame, a 85 pendulum weight suspended in the body of said aeroplane for automatically releasing said holding means when said aeroplane is tilted into a dangerous nose dive and for operating said means to lock the auxiliary plane in its released inclined position stabilizing the aeroplane, and a rebounding means for bringing said weight to action for releasing said stabilizing means to stabilize the aeroplane when tilted into a tail spin. 90 95

In testimony whereof I have affixed my signature.

SIMON YASULAITIS.
